Company, Lockland, Ohio, a corporation of
Ohio

Application February 1, 1933, Serial No. 654,588
Renewed October 18, 1937

12 Claims. (Cl. 154—30)

This invention relates to the production of paper and particularly to the production of two-way stretchable paper which may be used for various purposes, such for example as a lining for large sugar bags and other containers.

One object of the invention is a novel method and means for producing a paper of this character. A further object of the invention is a novel and improved machine for crinkling the paper stock in one direction, forming a multiplicity of longitudinal laterally yielding folds at right angles to the crinkles and preparing the same ready for use for linings of sugar bags and the like and other purposes. A further object of the invention is a paper particularly adapted for the above indicated purposes which is characterized by its freely stretchable character both laterally and longitudinally and by a pronounced degree of stretchability in one of these directions with the paper unimpaired. Further objects of the invention will hereinafter appear.

For a better understanding of the invention reference may be had to the accompanying drawings illustrating one embodiment thereof where-

25 in:
Fig. 1 is a diagrammatic view of a machine with certain parts broken away embodying the invention;

Fig. 2 is a detail of a part of the drive mechanism;

Fig. 3 is a view of certain parts broken away of another part of the drive mechanism;

Fig. 4 is a side view partly in section on the line 4—4 of Fig. 3 of another part of the drive mechanism;

Fig. 5 is a sectional view with certain parts in elevation through a part of the machine;

Fig. 6 is a front view with certain parts broken away of that mechanism;

40 Fig. 7 is a plan view of a part of the corrugating mechanism on a larger scale;

Fig. 8 is a view at right angles to Fig. 7 on the line 8—8;

Fig. 9 is a sectional view on the line 9—9 of Fig. 7;

Fig. 10 is an enlarged detail corresponding to Fig. 8;

Fig. 11 is a side view of the tensioning mechanism for the cord;

50 Fig. 12 is a schematic view indicating one way by which the corrugating and drive cord may be wound;

Fig. 13 is a view of the squeezer rolls;

Fig. 14 is a plan view of the product resulting 55 from the machine; and

Fig. 15 is a cross sectional view along the line 15—15 of Fig. 14.

The invention has to do with the production of the paper product indicated at 200 in Figs. 14 and 15. This paper is made of a paper stock suitable for the particular purpose, as for example of the paper stock used for the lining of large sugar bags and the like. The paper when finished for use comprises the crinkles 201 formed in one direction, as for example laterally of the paper stock strip worked upon and the overlapping or folded over parts 202 formed at an angle to the crinkles or, as indicated in the drawings, substantially at right angles thereto, as for example longitudinally of the paper stock strips. The paper 10 thus formed is stretchable in one direction, as for example longitudinally by the give due to the crinkles 201, while at the same time it is stretchable at right angles thereto to a considerably greater extent by reason of the pronounced folds 20 202 formed longitudinally of the paper. The longitudinal folds are formed in opposed pairs as indicated. The following is a description of the method and apparatus for forming this paper:

Referring to Fig. 1 of the drawings the invention is illustrated as embodied in a machine comprising a crinkling mechanism A, a second treating mechanism B and a drying mechanism C. The crinkling mechanism A may be of any suitable or standard form comprising, for example, a framework indicated at 100, a tank 101 with a perforated drum 102 immersed therein over which the paper stock indicated at 103 runs and is moistened thereby, a tank 104 in which runs the crinkling roller 105 and a doctor blade 106. The paper stock 103 after it is crinkled is conveyed by a belt conveyor 107 either directly to a belt conveyor 108 leading to the drying mechanism C, or directly to a conveyor mechanism indicated generally at 109 leading to the mechanism B, and 40 then ultimately to the conveyor 108. At 110 is indicated diagrammatically a means for printing or stamping a trade-mark upon the paper stock 103, while the paper stock is fed from a roll 103'.

The mechanism B, for forming the longitudinal 45 folds 202 and rendering the stock 103 stretchable at right angles to the crinkling effected by the mechanism A, comprises a comparatively large and elongated cylindrical drum 1 which is closed at its ends by plates 2 and is carried by a shaft 3 50 which is journaled in suitable bearings 4 mounted on the framework 5. For the purposes of supplying heating means, such as steam, to the interior of the drum 1, the shaft 3 is made hollow and intake and outtake pipes 6 are shown for keeping 55

the cylinder 1 supplied with the heating steam, it being understood that the pipes 6 have suitable packing glands 8 for sealing the pipes 6 against the rotating shaft 3. The drum 1 rotates freely in the bearings 4.

The drum 1 is provided on its periphery with a multiplicity of closely disposed circular grooves 7, the axial extent of these grooves being at least as great as the width of the finished stock desired. In the particular embodiment shown these grooves are discontinued at 8, a substantial distance from the ends of the drum 1 to accommodate, if desired, original paper stock of a width projecting beyond the limits 8. The paper stock 103 after the crinkling in mechanism A is fed to the periphery of the drum 1 and is held in close contact therewith; while as a further step in the making of the product shown in Figs. 14 and 15 the crinkled stock is pressed into these grooves 7 by a means comprising a cord or cords 10 which at one end pass around the presser rollers 11 and at the other end pass around a common roller 12, there being a roller 11 for each groove 7, and each presser roller 11 having a width larger than the width of the groove 7 with which it is associated.

The rollers 11 are carried by shafts 13 which are freely journaled in bearing members 14 which in turn are mounted upon the circular disposed L-beam members 15, the bearing members 14 being secured to the beams 15 in any suitable manner, as for example by the bolts 16. The circular beams 15 are supported in any suitable manner from the framework, as for example by means of angle irons 17 fastened to elongated pieces 18, which in turn are fastened to the frame members 5. The whole framework in the particular embodiment shown is suspended by an extension 19. The rollers 11 are freely journaled upon the shafts 13 and cooperating with each roller 11 is a sheave or guide pulley 19 for guiding the cord 10 to its particular roller 11 and groove 7, the sheave or guide 19 being disposed in advance of its corresponding roller and carried by the shaft 13 which is immediately in advance of the shaft upon which the corresponding presser roller is journaled. The sheaves 19 are of substantially smaller diameter than the rollers 11 and in the particular embodiment shown being approximately one-half the diameter of the rollers. By providing the separate guide sheaves 19 in advance of the rollers, the latter may be provided with a flat peripheral surface 11', no guide groove for the cord being necessary in the presser roller, and accordingly the cords 10 may be pressed down more deeply namely to the bottom of the grooves 7 to form more pronounced corrugations. Another advantage in the particular embodiment shown is that the guide sheaves cause the cord 10 to approach the bottom of the groove 7 at most a small angle indicated at 20, the cord gradually engaging the stock 103 as indicated at 21 to gradually press the same into the groove so as to avoid undue stress or strain upon the paper stock and to facilitate the formation of the deep corrugations (Fig. 9). The rollers 11 are slightly spaced from the periphery of the drum and spaced at a greater distance than the depth or thickness of the paper, as indicated at 22 (Fig. 10) so as not to engage and impede the lateral feeding or working in movement of the paper over the drum periphery during the formation of these grooves. The presser rollers thereby cooperating with the guide sheaves and the cords to perform the step of

grooving the paper stock in a particularly advantageous manner. The presser rollers 11 and the guide sheaves 19 are arranged in the form of a V, as more particularly indicated in Figs. 6 and 7, the apex of the V being in advance with respect to the relative travel of the paper stock, the purpose of this being to progressively initiate the grooves in the paper stock from the center outwards in both directions. There are, therefore, two diverging lines of guide sheaves and presser rollers on the periphery of the drum, which lines upon a plane development would be straight lines, as indicated in Fig. 7. For convenience, therefore, the drum 1 is provided with an odd number of grooves, as for example in the particular embodiment shown there being eighty-seven (87) of these grooves, covering a length of the drum of forty-five inches where the drum is approximately thirty-six inches in diameter. A single guide sheave in the form of a roller 23 with a groove 24 cooperates with the centrally disposed presser roller 11' which forms the groove 7' in the center (Figs. 7 and 10), while for forming the two grooves next to the center groove a pair of sheaves 25 and 25' cooperating with the following pair of presser rollers are provided, and then a second pair of guide sheaves 26, 26' cooperates with the next succeeding pair of presser rollers and so on. The pairs of sheaves 25, 25', 26, 26', 27, 27' etc. are fixed to their respective shafts 13 to rotate therewith, while the presser rollers, as described above, freely rotate upon these shafts. The presser rollers are properly spaced laterally of the drum to cooperate with their respective grooves in part by the sheaves 25, 25', 26, 26', etc., in part by their own peripheries overlapping, as indicated at 30, 31 and in part by collars 32 which are fixed to certain of the shafts 13 on the inner sides of these rollers, and also in part by collars 33 which are fixed to the ends of certain of the shafts 13 and engaging the beam members 14.

Referring particularly to Figs. 8 and 10 the inner groove 7' is formed with a rounded edge or shoulder 34 over which the paper stock 103 can easily slide and work in when pressed into the groove by the cord, namely without abrading, tearing or otherwise impairing the paper stock; the presser rollers, as above described, being slightly spaced from the periphery of the drum 20 and the paper stock to permit the lateral free feeding movement of the stock. In a similar manner and for a similar purpose the outer wall 35 of each succeeding groove from the center is provided with a pronounced rounded shoulder 36 or edge 34', the inner wall 36 of each such succeeding groove from the center groove being preferably slightly rounded, as indicated at 37, the rounding 34' being much more pronounced than the rounded edge 37 since the feeding movement of the paper is mostly inwardly towards the center groove 7' and the same degree of bevel on the inner walls not being necessary as is desired on the outer walls.

The roller 23 in addition to its function as a guide sheave 24 for a cord functions also as a smooth guide for the paper stock as it is delivered to the drum from the conveyor 109 hereafter described, it being observed in Fig. 5 that the crinkled paper stock is fed to the drum 1 at a point beneath the same and between the roller 23 and the drum, the roller 23 being closely disposed to the drum periphery.

As above described, the cords pass around at one end the individual guide sheaves 19 and their

corresponding presser rollers in pairs and at the other end around a common roller 12. The roller 12 is illustrated as being without guide grooves for the cords but such grooves may be provided, if desired or necessary. In the particular embodiment shown the cords 10 are formed of loops of a single cord which is threaded about the sheaves and presser rollers and the common roller 12 instead of the provision of a multiplicity of separate cords for each pair or group of sheaves and presser rollers and the drive mechanism. This single cord arrangement is preferred among other reasons because of the ease of drive and the facility with which the tension on the cords or cord loops or equivalent may be uniformly maintained and in a comparatively simple manner. As above described the drum 1 is freely journaled in the frame and it is driven by the friction of the cord loops and moving paper stock thereupon. The whole is driven by means of a drive drum 88 the latter being mounted upon a shaft 89 which is journaled in the frame members 5 and driven by a sprocket 90, as more particularly hereinafter described. A sufficient number of the loops of the single cord 10 are carried around the drive drum 88 to positively drive the cord and the mechanism therewith without slippage between the cord and the drum 88 and in the particular embodiment shown the cord is looped around the drum 88 eighty-six times (86) as it is threaded back and forth between the various sheaves and presser rollers and the common guide roller. For facilitating the threading of the cord a series of idler rollers 91, 92, 93, 94, 95, 96, 97 and 98 are journaled in the framework and spaced from and about the drum 150 in the manner generally indicated in Fig. 5, these idlers guiding the cord or cord loops to the sheaves and presser rollers in a substantially radial direction. There are also provided two guide pulleys 99 which are carried by suitable brackets 99' up above the drum for guiding the cord to and from a tension maintaining mechanism 150, the latter comprising a multiplicity of weighted pulley-blocks 151, in the particular embodiment shown there being three of such weighted pulleys which are guided on suitable guides 152. A cord is guided by the pulleys 99 to and from stationary pulleys 153 of the tensioning mechanism 150, while other stationary pulleys 154 are disposed between the movable weighted pulleys 151. By means of this tensioning mechanism the exact tension desired upon the cord may be maintained, as for example by mounting different weights 155 upon the movable pulleys, and the slack of the cord is at all times taken up. The cord or belting may be of cotton, such as sash cord, or other soft and pliable material.

The cord may be threaded in any suitable manner, but in the particular embodiment shown it is threaded generally as follows:

Taking the cord, for example, as it leaves the left hand pulley 99 in Fig. 5, it passes over the guide rollers 93, 92, 91 and then radially inwardly to the guide sheave 24. From there it passes under the following presser roller 11' into the central groove 7' and then around the drum 1 to the common roller 12. From here it passes about the driving drum 88, under idler 98, over idlers 97, 95, 93, 92 and 91 and into the sheave 25', then again around the drum 1 to the roller 12 and about the same circuit back to sheave 26', and so on to sheave 28'. The next six loops follow in the same general direction and pass around

the drive drum 88 and guide rollers 98, 97, 95, 93 and 92 omitting the roller 91, while the next seven loops pass around the same circuit omitting both rollers 91 and 92. The next four loops pass around the drive roller 88 and idlers 98, 97, 95 and 94 and then radially into the corresponding sheaves; while the next eight loops pass around the drive roller 88 and idlers 98, 97, and 95 radially inwardly to the corresponding sheaves; the next four loops pass around the drive roller 88, the idlers 98, 97 and 96 and then radially inwardly; while the next four loops pass around the drive roller 88, idlers 98 and 97 and then radially inwardly to the corresponding guide sheaves; while the next six loops pass radially inwardly directly from the idler 98 to the corresponding sheaves 62' to 67' respectively. These various loops leading radially inwardly to the prime number sheaves are not shown in the sectional view of Fig. 5, but are indicated schematically in Fig. 12. The loop leaving the sheave 67' and passing eventually over roller 12 instead of leading to drum or roller 88 it leads to a guide pulley 160 and from thence to another guide pulley 161 and from there radially inwardly to a sheave 67. This loop then continues about the drum over roller 12 and all the remainder of the loops pass around the driving drum or roller 88, the first five going directly from idler 98 to the corresponding sheaves; the next four passing radially inwardly from idler 97, the next four from 96; the next eight from 95; the next four from 94; the next seven from 93; the next six from 92 and the remaining four over idler 91, the last loop leaving 91 going to sheave 25 thence around the drum to roller 12 and from the roller 12 over roller 88, idler 98, 97 and to the right hand take-off pulley 99 of Fig. 5.

It is clear from the above description that in the formation of the groove in the paper stock in the central groove 7' the cord 10 is in actual contact with the paper inside the groove for practically the whole circumference of the drum, namely from the first presser roller 11' (Fig. 5) all the way around to the common guide roller 12 and in the formation of the grooves in the paper stock from the center outwards in both directions, the length of the cord in actual contact with the paper in the grooves gradually diminishes until we reach the last two presser rollers 11'' (Fig. 5) when the length of cord in actual contact with the paper in the outside grooves is from a point some distance rearwardly of the roller 12 to slightly beyond the presser rollers 11''.

The next step in the process after the formation of the deep longitudinal grooves in the paper stock by means of the mechanism above described is the pressing of the paper stock into a flat sheet to form the folds 202. This is effected by means of a pair of presser or squeezer rollers 170 and 171, the former preferably being of metal and the latter preferably being rubber covered with a thick surface of rubber 172. These drums or rollers are mounted upon shafts 173, 174 journaled in bearings 173' and 174' which bearings 65 are carried by the frame members 175, which frame members are mounted upon the framework 5. The bearing blocks 173' are fixed, while the bearing blocks 174' are movably guided in the guides 175 and springs 176 are disposed between the bearing blocks 173' and 174' at either end of the shafts which tend to separate the blocks. The movement of the blocks 174' away from the blocks 173' is limited by adjustable set screws 177 and by adjusting these screws the amount of 75

pressure exerted by the rubber facing 172 upon the drum 170 and the paper stock coming therebetween may be adjusted. The purpose of the springs 176 is to facilitate separating the drums 5 when the paper is being threaded through, the adjusting screw 177 being then screwed outwardly. The shaft 173 is driven in a manner hereinafter set forth and the paper stock 103, as it comes from the drum 1, that is over the guide roll 12, passes substantially vertically downwardly between these flattening rolls 170 and 171 and eventually falls upon the conveyor 108 (Fig. 1) which conveys the stock to the drying mechanism C. The drier C may be of any suitable type and will 10 be more particularly referred to hereinafter.

The paper stock when passing through the mechanism B is formed with the deep closely disposed longitudinal corrugations as indicated in Figs. 8 and 9, and upon passing between the 15 flattening rollers 170 and 171 the corrugations are ironed and pressed out to form a substantially flat sheet with the longitudinal well defined opposed folds 202 which give the paper the substantial and marked lateral stretchability, without injury or impairing the stock. The folds formed in the paper together with the treatment in passing through the machine is usually sufficient to reduce the width to two-thirds of the original width of the stock 103 prior to its entry into the mechanism B.

The conveyor 109 which transfers the paper stock from the crinkling mechanism A to the mechanism B is of the belt conveyor type, as will be described, and may be of any suitable width 20 but in the particular embodiment shown is indicated of a width approaching the length of the drum 1 (Fig. 6).

The whole machine is driven by a motor 111 which is suitably positioned with respect to the 25 three elements A, B and C to be driven. It is coupled up to drive a shaft 112 by a sprocket chain 113 passing around suitable sprockets on the two shafts. The drive between the shaft 112 and the crinkling roller 105 is omitted for convenience in illustration. The shaft 112 directly drives a shaft 114 through a sprocket chain 115 passing over suitable sprockets carried by these two shafts. The shaft 114 is coupled to a shaft 116 through a small sprocket 117, a chain 118 and a larger sprocket 119 on the shaft 116. The shaft 116 in turn drives the conveyor mechanism 120 of the drier C through a sprocket chain 121 passing over two lower sprockets 122, a small sprocket on the drive shaft 116 with one of the loops of the 30 chain 121 passing between the alternating sprockets 123 of the drier conveying mechanism. It also drives the belt conveyor 107 and 108 through a sprocket 124 which guides the sprocket chain 121 downwardly to the sprockets 123 and a 35 sprocket 126 being mounted upon a shaft around which the conveyor 108 passes at its lower end. On the shaft 125 is mounted a sprocket 126 which is coupled to a smaller sprocket 127 on the shaft around which the upper end of the conveyor 107 40 passes, thereby driving the continuous conveyor 107. Shaft 114, as will hereinafter appear, is coupled up to drive conveyor 109 and the mechanism B.

The conveyor 109 comprises two mating or 45 complementary conveyors mounted on a suitable framework 130 and comprises a continuous conveyor 131 on one side of the stock 103 and a corresponding or complementary conveyor 132 on the other side of the stock 103. These conveyors are 50 guided over idling rollers, as indicated more par-

ticularly in Fig. 5, a fixed idler 133 adjacent the lower end of the frame 130, a set of three fixed idlers 134, 135 and 136, a set of three adjustable idlers 137, 138 and 139, a set of fixed idlers 140, 141 and 142 still further up on the frame member 130, a pair of driven rollers 143 and 144 journaled upon the upper end of the frame 130 and a normally fixed idler 145 carried by an adjustable bracket 146 from the lower end of the frame 130. The bracket 146 projects down to a point in proximity to the upper end of the conveyor 107 with the idler 145 so as to enable the conveyor 131 which is inclined at that point to receive the crinkled stock 103, and guide it up to the idler 133 about which the lower end of the conveyor 132 passes. The two adjacent loops of the conveyors 131 and 132 pass to the right of idler 135 and to the left of idler 138 and to the right of idler 141 and then between the two drive rollers 143 and 144, it being noted that these idler rollers 135, 138 and 141 are out of alignment with each other to cause a slightly tortuous passage for the conveyance of the stock 103 between the two conveyor elements. A particular advantage of the offsetting of the rolls for the conveyors 131 and 132 is to cause the conveyor elements to follow a path which is rectilinear only between adjacent guide rollers, so that the inside bands of the conveyors 131 and 132 snugly and firmly engage the paper on both sides and thereby facilitate the conveyance of the paper stock and avoid slippage. The idlers 137, 138 and 139 are carried by an adjustable bar 147 slideable in a guide frame 148 and adjustable back and forth by means of an adjustable screw 149 passing through one end of the frame 148 and engaging the slide bar 147.

The shaft 114 is driven from the motor 111 as described above and from this shaft the driven drum 88 and the squeezer rolls 170 and 171 and conveyors 131 and 132 are driven. Mounted adjacent the shaft 114 is another shaft 180, this shaft also being journaled in the frame members 5. These two shafts are geared together by the gears 181 and 182, the gear 182 being keyed to the shaft 180 and the gear 181 being loose upon the shaft 114 but capable of being clutched thereto by means of a manually operated clutch 183 through a handle 183'. The shaft 180 is geared to the shaft carrying the drum 88 through a sprocket chain drive 174, thereby effecting the 5 drive of the cord, the sheaves, presser rollers and drum 1 together with the feeding of the paper stock through that part of the mechanism. The shaft 180 is also geared to the shaft 173 through a sprocket chain drive 185 and thereby 5 driving the shaft 173 and the shaft 173 is geared to the shaft 174 through the meshing gears of equal diameter 186. The squeezing rolls 170 and 171 are thereby driven to flatten the paper stock out and to form the folds 202 therein as above 6 described and to feed the paper stock to the conveyor 108 leading to the drier C. The conveyors 131 and 132 are driven from the shaft 174 by means of a sprocket chain drive 143' between the shaft 174 and the shaft 143, the latter being geared to shaft 144 through meshing gears 144'. The conveyors 131 and 132 are composed of a multiplicity of complementary belts intermediate the edges, while at the edges there are single belts 131', which are wider than 131 70 and 132 to give a more positive drive.

As above described, therefore, the motor 111 drives all of the cooperating mechanism of the machine for the production of the product illustrated in Figs. 14 and 15.

The bracket 146 is adjustable to the dotted positions indicated in Figs. 4 and 5 to permit, if desired, the delivery of the crinkled stock 103 direct from the conveyor 107 to the conveyor 5 108 leading to the drier C. This enables the production of a paper which is merely crinkled for stretchability in one direction only in which case the manually operated clutch 183 is disengaged to stop the rotation of the shaft 180. This 10 bracket 146 may be, of course, adjusted and held in any position by any suitable mechanism but the means shown diagrammatically for this in the particular embodiment shown comprises a pin 190 in each arm 146 which pin when the arm 15 is in its lower position engages holes 191 and when it is raised to the position shown in Figs. 4 and 5 these pins engage holes 192 and the frame 130.

An important feature of my improved machine 20 as above described is that the crinkled paper is conveyed in moist and heated condition from the crinkling cylinder through the corrugating and flattening devices, and this is accomplished without materially stretching the crinkled paper 25 longitudinally and without danger of rupturing or otherwise weakening the fibers of the paper. The mated conveyors 131 and 132 bodily carry the paper from near the crinkling cylinder to a position in proximity to the corrugating cylinder, and the cord or belting cooperates with the grooved corrugating cylinder to bodily carry the paper to a position in proximity to the flattening rolls. Only sufficient longitudinal tension is placed on the paper as it passes between these 35 devices to take up slack so as to prevent wrinkling. As the crinkled paper leaves the mated conveyors 131 and 132 it is gradually guided toward the bottom of the grooves in the cylinders by the inclined portions of the belting which 40 extend from the forward sheaves to the presser rolls 11, and the presser rolls acting through the belting firmly mold and lay the paper into the grooves, the soft and pliable belting exerting a cushioning action on the paper as it is pressed into the grooves. The portions of the belting 45 extending into the grooves firmly but yieldingly hold the paper therein as adjacent corrugations are being formed so that there is no danger of the paper working out of the grooves. As the 50 paper passes about the cylinder the heat of the cylinder not only tends to dry the paper but also prevents the wax, in the case of wax coated paper, from becoming set previously to the flattening operation. The single length of belting 55 for the several grooves may be maintained only under sufficient tension to insure the proper holding of the paper in the grooves in the corrugating cylinder, and to insure uniform driving of the cylinder without danger of slippage occurring.

As will be evident to those skilled in the art, my invention permits various modifications without departing from the spirit thereof or the scope of the appended claims.

65 I claim:

1. In a paper working machine a movable paper gripping surface with a multiplicity of longitudinal grooves formed therein, a plurality of sheaves journaled in close proximity to said movable gripping surface, cords or gripping bands carried by said sheaves and maintained respectively in said grooves, means for supplying paper stock between said sheaves and the movable surface to be engaged between said cords and said 70 movable surface and means for driving said drum 75

and sheaves to progressively convey the paper stock between the cords and movable surface to form longitudinal corrugations in the stock, said cords being formed of a continuous cord, means for distributing the loops of the cord to and from the respective sheaves, and a single means for maintaining the desired tension on said cord. 5

2. In a machine of the character set forth in claim 1 wherein the cords are formed of a continuous cord with means for distributing the 10 loops of the cord to and from the respective sheaves, and a single means for maintaining the desired tension on said cord, comprising a movable weighted pulley block inserted in one of said cord loops. 15

3. In a machine of the character set forth in claim 1 wherein the cords are formed of loops of a single continuous cord, together with means for distributing the cord loops to and from the sheaves and driving the same, comprising a drive 20 drum about which the cord loops pass and are caused to frictionally engage. 25

4. A machine of the character set forth in claim 1 wherein the supply means comprise a pair of juxtaposed continuous conveyor belts 25 gripping said paper stock therebetween, said belts being guided in a zigzag path for the purpose set forth. 30

5. A machine of the character set forth in claim 1 wherein the sheaves are progressively 30 distributed along the movable surface with a single sheave for an intermediate groove followed by pairs of sheaves progressively laterally spaced the distance of the groove spacing, the two side walls of said intermediate groove being beveled 35 or rounded off to permit the free lateral feeding movement of the paper stock and each succeeding groove having its outer side wall similarly beveled off. 40

6. A machine of the character set forth in claim 1 wherein the sheaves are progressively distributed along the movable surface with a single sheave for an intermediate groove followed by pairs of sheaves progressively laterally spaced the distance of the groove spacing, the two side 45 walls of said intermediate groove being beveled or rounded off to permit the free lateral feeding movement of the paper stock and each succeeding groove having its outer side wall similarly beveled off, while its inner side wall is only slightly 50 beveled or rounded. 50

7. In a paper working machine a rotatable drum having a multiplicity of circular grooves formed in its periphery, a multiplicity of sheaves journaled in close proximity to said grooves and carrying cords which are caused to traverse and grippingly engage the bottoms of said grooves, means for feeding paper stock between the sheaves and cords and the drum and means for rotating said drum with the cords engaging the 60 paper stock and pressing it into the grooves while it is thus being advanced, said cords disposed in said grooves being made up of loops of a single cord threaded about the sheaves, a drive drum about which said cord passes and frictionally engages for the purpose of conveying and advancing the paper stock with the rotation of the drum and corresponding advancement of the cord loops, and means for pressing and flattening out the corrugations thus formed in said paper stock. 65 70

8. In a paper working machine a rotatable drum having a multiplicity of circular grooves formed in its periphery, a multiplicity of sheaves journaled in close proximity to said grooves and carrying cords which are caused to traverse and 75

- grippingly engage the bottoms of said grooves, means for feeding paper stock between the sheaves and cords and the drum and means for rotating said drum with the cords engaging the paper stock and pressing it into the grooves while it is thus being advanced, an intermediate sheave cooperating with an intermediate groove with pairs of sheaves following the first sheave and progressively distributed to successive grooves 5 whereby the corrugations are progressively formed in the advancing paper stock from the center outwardly, with the first sheave formed in a guide roll for guiding the paper stock between the cords and the drum, and means for pressing 10 and flattening out the corrugations thus formed in said paper stock.
9. In a paper working machine a rotatable drum having a multiplicity of circular grooves formed in its periphery, a multiplicity of sheaves 20 journaled in close proximity to said grooves and carrying cords which are caused to traverse and grippingly engage the bottoms of said grooves, means for feeding paper stock between the sheaves and cords and the drum and means for 25 rotating said drum with the cords engaging the paper stock and pressing it into the grooves while it is thus being advanced, means for supplying a heating fluid to the interior of the drum, and means for pressing and flattening out the corrugations thus formed in said paper stock.
10. In a paper working machine, a rotatable drum having a multiplicity of closely disposed circular grooves formed on the periphery thereof, a plurality of sheaves one for each groove 30 journaled in close proximity to the periphery of
- the drum, said sheaves after the first and centrally disposed sheave being distributed in pairs circumferentially about the drum at distances progressively radiating from the center of the drum, a common sheave also journaled in close proximity to the periphery of the drum, with cord loops guided by the individual sheaves and the common sheave and maintained in gripping engagement with the bottoms of the grooves, a driving drum about which said cord loops pass, said 1 loops being formed of a continuous cord which are radially distributed to the sheaves by idlers distributed about the drums, a tension mechanism comprising weighted pulleys about which one loop of said cord passes, the first or centrally disposed sheave comprising a feed roll journaled in close proximity to the periphery of the drum, and means for supplying a paper strip between said roll and drum to be engaged between said cord loops and said drum and means for driving said 21 drive drum.
11. In a machine of the character set forth in claim 10 comprising a plurality of non-grooved presser rollers journaled in close proximity to the periphery of the drum and engaging the cord 25 loops to press them into the grooves but not engaging the paper stock, there being a presser roller immediately following each of said sheaves and the latter having their surfaces further removed from the peripheral surface of the drum 30 than the surfaces of the presser rollers.
12. In a machine of the character set forth in claim 10 comprising means for supplying a heating fluid to the interior of said drum.
